UNITED STATES PATENT OFFICE.

WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINOTYPE-MACHINE.

1,116,219.

Specification of Letters Patent.

Patented Nov. 3, 1914.

Application filed November 23, 1911. Serial No. 661,943.

To all whom it may concern:

Be it known that I, WILLIAM E. BERTRAM, a citizen of the United States, residing at Brooklyn, in the county of Kings and State of New York, have invented new and useful Improvements in Linotype-Machines, of which the following is a specification.

The present invention relates to improvements in linotype machines and more particularly to the matrix delivery mechanism thereof, and the object of this invention is to provide simple and improved means for automatically effecting the delivery of matrices bearing the same character alternately from different channels of the magazine by the return movement of the line carriage, thereby enabling the machine to handle an extra supply of matrices bearing the character or characters most frequently used, to the end that there will be no delay in the operation of the machine due to the temporary exhaustion of certain matrices.

To these and other ends, the invention consists in certain improvements, and combinations and arrangements of parts, all as will be hereinafter more fully described, the novel features being pointed out particularly in the claims at the end of the specification.

30 In the accompanying drawing:—Figure 1 is a side elevation partly in section of a portion of the magazine and the mechanism for causing matrices to be alternately delivered from different magazine channels; 35 Fig. 2 is a front elevation of the parts shown in Fig. 1; Fig. 3 is a detail sectional view on the line 3—3 of Fig. 2; and Fig. 4 is a detail perspective view of the controlling cam.

40 Similar parts are designated by the same reference characters in the several views.

In operating linotype machines and especially those of the Mergenthaler type, a considerable number of the matrices are 45 passing through the machine and at times a large number of the most frequently used matrices have been drawn from the magazine, and experience has shown it to be necessary to provide an extra supply of 50 matrices bearing the most frequently used characters, such, for example, as the letter "e", these matrices bearing like characters being contained in different channels of the magazine and such matrices are delivered 55 alternately from the respective channels,

therby providing for a sufficient supply of matrices to avoid interruption in the operation of the machine and without increasing the size of the magazine in order to accommodate the extra supply of matrices.

The present invention provides simple and improved means for effecting the alternate delivery of the matrices bearing like characters from the different magazine channels by the return movement of the line carriage. In the present instance, the lower corner of the magazine 1 is shown and the matrices bearing the same characters are contained in adjacent channels 2 and 3 of the magazine. The delivery of matrices from both of these channels is controlled by an escapement embodying a rocking member 4 fulcrumed on the pivot 5 and operatively connected to the escapement pawls 6 and 7, these escapement pawls being of a width sufficient to extend across both of the magazine channels and they coöperate in the usual way with the matrices to permit delivery thereof one at a time.

Actuation of the escapement to effect the delivery of a matrix is caused by the usual matrix delivery bar 8 which is controllable from the keyboard in the well known manner. Each actuation of the escapement will simultaneously release a matrix in each channel. Means, however, is provided for preventing the delivery of one of the released matrices and to permit the delivery of the other released matrix, the matrix retaining means being operative automatically to cause the delivery of the matrices alternately from the respective channels. The matrix retaining means in the present instance embodies a pair of retaining pawls 9 and 10, these pawls being pivoted on a pin 11 supported by the bearing lugs 12 on the upper side of the magazine, and these retaining pawls have bent or hook-shaped fingers 13 and 14 which are adapted to be lowered into alignment with the respective magazine channel and to engage the forward edge of the foremost matrix therein. These retaining pawls are provided with springs 15 which tend to hold the pawls in inoperative positions or in positions clear of the matrices. Means, however, is provided for shifting the retaining pawls alternately into reverse positions whereby one pawl will prevent delivery of matrices from its respective magazine channels, while the other pawl will occupy an

inoperative position and will permit delivery of a matrix from its respective channel. Such means consists in the present instance of a cam which in the form shown embodies a sleeve 16 provided with alternately or reversely positioned cam projections 17 and 18, these projections being spaced in alternate relation with respect to the circumference of the cam. The cam is pinned or otherwise keyed to an actuating shaft 19, this shaft being mounted in suitable bearings 20 on the upper side of the magazine and a ratchet wheel 21 is fixed to the shaft, this ratchet wheel having teeth 22 which correspond in number to the number of cam projections, and these ratchet teeth are spaced in predetermined relation to the cam projections.

An actuating arm 23 is turnably mounted 20 on the shaft 19 and it carries a spring-pressed pawl 24 which, when the actuating arm is turned in one direction, will engage a tooth on the ratchet wheel 21 and rotate the latter one step, the cam being correspondingly rotated whereby one of the matrix retaining fingers will be moved by its respective cam projection into position to engage the foremost matrix in its corresponding channel to prevent delivery of such matrix while the other retaining pawl will be permitted to move into an inoperative position by its spring whereby a matrix may be delivered from its corresponding magazine channel, the relation of the retaining pawls being reversed by the next step in the rotation of the ratchet wheel 21. To insure proper operation of the escapement, each retaining pawl when it moves into operative position preferably has a movement sufficient to push the foremost matrix rearwardly in its corresponding channel so that the shoulder 25 on the matrix will disengage from the escapement pawl 7 so that this escapement pawl will reengage the shoulder 25 with certainty after a matrix has been delivered from the other channel.

The actuating arm 23 for the reversing cam is, according to the present invention, actuated at appropriate intervals from the line delivery carriage 26 when the line carriage begins to deliver the composed line of matrices and spacers, the line carriage being provided for this purpose with an operating projection 27 to coöperate with a latch 28, the latter being turnable on a stationary pivot 29 and it has an operating shoulder 30 to coöperate with an operating arm 31, the latter being mounted to turn on the pivot 29, and the shoulder 30 is yieldably held in engagement with the arm 31 by a tension spring 32. A link 33 is pivotally connected to the arm 31, and the upper end of this link is operatively connected to a lever 34, the latter being turnable on a stationary pivot 35 and it has a

slot 36 which operatively engages a pin or projection 37 on the ratchet-actuating arm 23. A spring 38 returns the link 33 and the connected parts to normal position after each actuation thereof by the line carriage. 70 Each delivery movement of the line carriage 26 toward the left in Fig. 2 causes the projection 27 thereon to engage the latch 28 and turn the latter about its pivot 29, the shoulder 30 on the latch bearing on the arm 75 31 and causing the latter to be turned also about the pivot 29. In this manner, the bar 33 moves downwardly and the slotted end of the lever 34 moves upwardly carrying with it the pin or projection 37 on the actuating arm 23 and thereby causing the ratchet wheel 21 to rotate one step, and owing to the operative relation between the cam and the ratchet wheel, one of the retaining pawls 80 will permit delivery of a matrix from one magazine channel, and the other retaining pawl will prevent delivery of a matrix from its respective channel.

During the movement of the line carriage, the operating projection 27 thereon will trip 90 past the latch 28 owing to the arcuate path of movement of the lower end of this latch, and when the line carriage returns to initial position or moves toward the right in Fig. 2, the operating projection 27 will trip past 95 the latch, as illustrated diagrammatically by the dotted lines in this figure, this tripping action being permitted owing to the pivotal relation between the latch and the arm 31 and the yielding of the spring 32 100 which connects such parts. It is therefore obvious that a sufficient supply of matrices is provided for by the plural number of magazine channels, and that the matrices are delivered uniformly from the different 105 channels owing to the alternate action of the matrix retaining pawls. It is to be understood that the shaft 19 can be extended and provided with additional cams and retaining pawls in order that matrices may be delivered alternately from additional double 110 matrix channels of the magazine.

It is advantageous to govern the delivery of matrices from the different magazine channels from the line delivery carriage as 115 the latter operates to reverse the matrix delivery mechanism so as to draw the matrices from the alternate channels immediately after each line has been composed and while such line is being delivered, a supply of the 120 desired matrices being thereby insured at the commencement of the composition of each line.

I claim as my invention:

1. In a machine of the linotype class, 125 the combination with a magazine having a plurality of matrix containing channels, escapement means operative to cause delivery of matrices from such channels, and a reciprocatory line delivery carriage, of means 130

for causing delivery of matrices alternately from different magazine channels embodying a member located in the path of movement of the line delivery carriage and operative by said carriage during the line delivery movement thereof.

2. In a machine of the linotype class, the combination with a magazine having a plurality of matrix containing channels, especially 10 capement means operative to deliver matrices from such channels, and a reciprocatory line delivery carriage, of means for causing delivery of matrices alternately from different magazine channels embodying a pivoted lever arranged in the path of movement of the line delivery carriage and actuated by said carriage when the latter moves in one direction and permitting reverse reciprocation of said carriage without producing operative movement of said lever.

3. In a machine of the linotype class, the combination with a magazine having a plurality of matrix containing channels, especially 25 capement means operative to cause delivery of matrices from said channels, and a reciprocatory line delivery carriage carrying an actuating projection, of means for causing delivery of matrices alternately from said channels embodying a lever pivoted on a

fixed axis relatively to said carriage and having a portion arranged in the path of the actuating projection on the carriage, said projection actuating said lever and disengaging therefrom during movement of the line delivery carriage in one direction.

4. In a machine of the linotype class, the combination with a magazine having a plurality of matrix containing channels, especially 40 capement means operative to deliver matrices from said channels, and a reciprocatory line delivery carriage having an actuating projection movable therewith, of means for causing delivery of matrices alternately from said magazine channels embodying a lever pivoted on a fixed axis and operative in one direction by said projection and automatically disengaging therefrom when the line delivery carriage moves in one direction and movable idly in a reverse direction by 45 said projection during a reverse movement of the line delivery carriage.

In testimony whereof I have hereunto set my hand in presence of two subscribing witnesses.

WILLIAM E. BERTRAM.
